(57) **CLAIM**

The ornamental design for a document carrying case, as shown and described.

DESCRIPTION

FIG. 1 is a perspective view of the document carrying case. FIG. 2 is a right end view of the document carrying case. The left end is a mirror image of the right end.

FIG. 3 is a front view of the document carrying case. The rear is identical to the front.

FIG. 4 is a top view of the document carrying case; and, FIG. 5 is a bottom view of the document carrying case.

1 Claim, 3 Drawing Sheets

FIG. 3

FIG. 2

FIG. 4

FIG. 5
